UNITED STATES PATENT OFFICE.

BENJAMIN F. FITCH, OF GREENWICH, CONNECTICUT.

TURNTABLE CRANE.

Application filed February 12, 1925. Serial No. 8,620.

This invention relates to hoisting and conveying apparatus and is particularly concerned with a crane which is adapted to travel on an overhead track, and to be used in connection with the operation of a system for handling freight wherein the freight is stored in removable bodies or containers which may be transferred to and from automobile trucks.

10 In handling freight by such a system, it is desirable to adapt the apparatus to existing structures without requiring extensive changes to be made in the construction of warehouses, platforms or runways adjacent thereto. The height of a removable container which has been found to give most satisfactory results in handling freight, and the desirable amount of lift, precludes sufficient head room within the average warehouse or freight station for the use of standard traveling cranes. It is one of the objects of my invention to obviate the necessity for expensive alterations to provide space or strength to render existing structures safe 20 for handling loaded containers by means of an overhead crane.

One of the features of my invention therefore, is the provision of a crane which possesses a minimum depth, yet will have sufficient power to raise a loaded container in the form of a removable body and transport it along an overhead trackway to or from a truck. Thus the crane may be satisfactorily used in existing warehouses, or freight stations, without altering the building construction, and without interfering with the normal flow of traffic within the station.

25 The means for carrying out my invention is illustrated in the preferred form in the accompanying drawings, wherein Fig. 1 is a plan view of a crane embodying my invention and showing one position of the supplemental frame with reference to the main frame; Fig. 2 is a similar view showing the supplemental frame in a different position from that shown in Fig. 1; Fig. 3 is a side elevation of the crane; Figs. 4 to 6 are sections taken on an enlarged scale on planes indicated by the lines 4-4 to 6-6 respectively in Fig. 1; Fig. 7 is a plan view of the supplemental frame apart from the main frame, and Fig. 8 is a section on an enlarged scale indicated by the line 8-8 in Fig. 7.

30 My invention is shown in connection with

an overhead hoisting mechanism which is employed for engaging, raising and transporting removable automobile bodies. Accordingly, in the various figures 10 indicates a set of overhead tracks along which wheels 60 11, journalled with an overhead crane, are adapted to travel. The crane as illustrated comprises a main frame and a supplemental frame, which is mounted within and is arranged to be turned with reference to the main frame. The supplemental frame carries load engaging and hoisting mechanism, wherefore a load may be engaged raised and turned with reference to the main frame and then transported along the trackway.

35 The main frame in the preferred form comprises longitudinally extending members 12 and transversely extending members 13 which are arranged in the form of a rectangle. The frame work preferably comprises channel beams which are held together in any suitable manner and which are of such size as may be necessary to support the load. The main frame as shown has a curved trackway 20 in the form of an endless beam. An inwardly extending flange on the beam supports wheels 43 which are journalled in the supplemental frame.

40 To propel the main frame along the trackway, I have illustrated one pair of wheels 85 11 as being operatively connected by gears 8 and 9 to a motor 23. The motor preferably is reversible wherefore the direction of movement of the main frame may be determined by the direction of rotation of the motor.

45 The supplemental frame is indicated as having longitudinal members 40, which are connected at the ends by transverse members 41, and are arranged to support wheels 95 43 which travel on the curved trackway. The axes of the wheels extend radially of the trackway wherefore the supplemental frame may be turned a complete revolution with reference to the main frame.

50 The supplemental frame supports the hoisting mechanism which is illustrated as comprising flexible load engaging members 50, 51, 52 and 53 which extend over sheaves 54, 55, 56, and 57 respectively. The sheaves therefore are arranged to define a rectangle wherefore the cables may engage a removable automobile body at four points. Moreover, the sheaves are near the radial supporting wheels, wherefore the size of the sup-

plemental frame is determined by the distance between the sheaves, which in turn is controlled by the size of the automobile body in which the load is carried.

5 To raise and lower the cables as a unit, I have shown a drum 60 which is mounted for rotation upon a vertically extending shaft 61. The shaft is indicated as being supported in beams 62 and 63 which extend 10 across the supplemental frame. One end of each flexible raising member or cable is arranged to be attached to the drum wherefore rotation of the drum in one direction causes the cables to be wound in simultaneously, 15 while rotation of the drum in the opposite direction enables the cables to be payed out simultaneously.

To rotate the drum, I have indicated an electric motor 64 which is carried by the 20 supplemental frame and which is connected by gearing 65 to a shaft 45. A member 66 splined to the shaft and forming the shiftable member of a dog clutch may be used for effecting rotation of shaft 67 through the 25 medium of a driven clutch member 68 tight on that shaft. The shaft 67 is indicated as having a worm 69 connected with a worm wheel 70 on shaft 71. A pinion 72 on the shaft 71 meshes with a circular rack 73 30 mounted on the drum. The worm and worm wheel connection provide a lock for suspending the load when the motor drive is disconnected.

The clutch sleeve 66 is also adapted to be 35 moved out of engagement with the clutch member 68, and to engage a clutch member 74 which is rigid with a gear 75. This gear meshes with a gear 76 on a shaft 77, whereby one of the wheels 43 rigidly mounted on the shaft 77 is rotated whenever the gear 75 40 is turned. Since the motor 64 can be a reversible motor, then the direction of rotation of the supplemental frame can be controlled at will.

45 By employing a drum which has a relatively large diameter, then one revolution of the drum is ordinarily sufficient to raise the load the maximum distance. This permits the use of a narrow drum and provides 50 a crane frame having a short overall depth. Accordingly the crane may be employed in low buildings without necessitating extensive changes in the construction thereof. Moreover the drum leaves ample space in the supplemental frame for the installation of mechanism to turn the supplemental frame and to actuate the hoisting apparatus. Thus, I obtain a crane which is quite simple in construction and which is durable in use.

55 Having thus described my invention, I claim:

1. In a crane, the combination with a main frame, of a supplemental frame rotatably carried by the main frame, a drum 65 mounted for rotation upon a vertical axle

coincident with the axis of rotation of the supplemental frame, and load engaging members leading from the drum.

2. In a crane, the combination with a frame, of a drum mounted to rotate upon a vertical axis within the frame, and flexible load engaging members leading from the drum to four points on the frame spaced respectively at the four corners of a rectangle. 70

3. In a crane, the combination with a frame, of sheaves rotatably mounted upon the frame and disposed adjacent the corners of a rectangle, a drum mounted upon a vertical axis within the frame, and flexible load engaging members leading from the drum 80 and extending downwardly from the frame so as to engage the load at four points. 75

4. In a crane, the combination with a main frame, of a supplemental frame rotatable therein, a drum mounted to rotate upon a vertical axis within the supplemental frame, and flexible load engaging members leading from the drum to spaced points on the supplemental frame. 85

5. The combination with a main frame, 90 of a supplemental frame traveling substantially within the upper and lower confines of the main frame, one of said frames having an endless trackway and the other having rollers coacting therewith, a vertically 95 positioned drum within the supplemental frame, cables leading from the drum and extending downwardly from the supplemental frame, and means for rotating the drum to wind in or pay out the cables simultaneously. 100

6. In a crane, the combination with a main frame having an endless trackway thereon, of a supplemental frame having wheels riding on the trackway, a drum mounted for rotation upon a vertical axis within the supplemental frame, cables leading outwardly 105 from the drum to spaced points on the supplemental frame, the drum having such size that the maximum lift of the cables may be accomplished by substantially a complete 110 revolution of the drum.

7. In a crane the combination with a main frame, of a supplemental frame mounted for rotation within the main frame, a drum mounted for rotation upon a vertical axis 115 within the supplemental frame and adapted to be rotated independently of the supplemental frame, sheaves carried by the supplemental frame and disposed adjacent the corners of a rectangle, cables each having one end attached to the drum and leading outwardly over one of the sheaves, and means on the supplemental frame for rotating it with reference to the main frame and for rotating the drum. 120

8. In a crane, the combination with a rotatable frame of a drum mounted to rotate upon a vertical axis coincident with the axis of rotation of the frame, cables leading from the drum to spaced points on the frame, said 130

drum having gear teeth associated therewith, a pinion meshing with said teeth and means on the frame for rotating said pinion.

9. In a crane, the combination with a frame of sheaves carried thereby and disposed adjacent the corners of a rectangle, a drum mounted for rotation upon a vertical axis adjacent the mid-portion of the frame, cables leading outwardly from the drum over the respective sheaves and adapted to engage and suspend a load, the drum having gear teeth on the underside thereof, a pinion meshing with said teeth, an electric motor mounted on the frame and operatively connected to the pinion, there being a worm and worm wheel connection between the motor and pinion, the pitch of the worm teeth being such that a load suspended from the cables is prevented from rotating the drum when the motor is stopped.

10. In a crane, the combination with a main frame having a curved trackway carried thereby and disposed within planes defining the top and bottom of the main frame, a supplemental frame, wheels carried thereby and engaging the curved trackway, a drum mounted upon a vertical axis for rotation within the supplemental frame and adjacent the mid-portion thereof, cables leading outwardly from the drum to spaced points on the supplemental frame, an electric motor mounted on the supplemental frame, means for selectively effecting an operative connection between the motor and

the drum, said means including mechanism for also effecting an operative connection between the motor and one of said wheels, whereby the supplemental frame may be turned independently of said drum.

11. In a crane, the combination with a main frame adapted to travel on an overhead trackway, an endless trackway carried by the main frame, a supplemental frame having wheels traveling on the trackway, the supplemental frame being disposed within planes which define the top and bottom of the main frame, a drum mounted for rotation upon a vertical axis within the supplemental frame, sheaves carried by the supplemental frame and disposed adjacent the corners of a rectangle, cables leading outwardly from the drum and extending downwardly from the said sheaves for engaging a load at four points, the diameter of said drum being such that the maximum lift can be attained on substantially one complete revolution of the drum, said drum having gear teeth associated therewith, a pinion meshing with said teeth, an electric motor carried by the supplemental frame, manually operable means for effecting a selective engagement either between the motor and said pinion to rotate the drum, or between the motor and one of said wheels to turn the supplemental frame with reference to the main frame.

In testimony whereof, I hereunto affix my signature.

BENJAMIN F. FITCH.
